UNITED STATES PATENT OFFICE.

JAMES N. WILSON, OF MINNEAPOLIS, MINNESOTA, ASSIGNOR OF TWO-THIRDS
TO O. H. LEONARD AND R. S. ASHTON, OF PIPESTONE, MINNESOTA.

STRAW-STACKER.

SPECIFICATION forming part of Letters Patent No. 642,406, dated January 30, 1900.

Application filed July 17, 1899. Serial No. 724,025. (No model.)

To all whom it may concern:

Be it known that I, JAMES N. WILSON, a citizen of the United States, residing at Minneapolis, in the county of Hennepin and State 5 of Minnesota, have invented certain new and useful Improvements in Straw-Stackers; and I do hereby declare the following to be a full, clear, and exact description of the invention, such as will enable others skilled in the art to 10 which it appertains to make and use the same.

My invention relates to straw-stackers of the general character set forth and claimed in my Patent No. 630,279, of date August 1, 1899, entitled "Straw-Stacker," and has for its object to improve the same in the several particulars hereinafter noted.

To these ends my invention consists of the novel devices and combinations of devices hereinafter described and defined in the 20 claims.

The invention is illustrated in the accompanying drawings, wherein, like characters indicating like parts throughout the several views—

25 Figure 1 is a view in right-side elevation with some parts broken away, showing a portion of a thresher with my improved stacker applied thereto. Fig. 1^a is a view in right-side elevation with some parts broken away, 30 showing the outer portion of the stacker, said view being supplemental to Fig. 1. Fig. 2 is a view in left-side elevation, showing the parts of the thresher and stacker illustrated in Fig. 1. Fig. 2^a is a view in left-side elevation, showing a section of the stacker illustrated in Fig. 1^a, said view being supplemental to Fig. 2. Fig. 3 is a plan view of a portion of the stacker-supporting connection. Fig. 4 is a detail in front elevation, showing 40 a guiding device for the stacker-supporting connection. Fig. 5 is a vertical longitudinal section with some parts shown in full, taken approximately centrally through the parts illustrated in Fig. 2. Fig. 5^a is a vertical longitudinal section of the outer portion of 45 the stacker, said view being supplemental to Fig. 5. Fig. 6 is a transverse vertical section taken through a portion of a stacker approximately on the line $x^6 x^6$ of Fig. 5. Fig. 50 7 is a plan view of a portion of the stacker-truck. Fig. 8 is a vertical longitudinal sec-

tion taken through a portion of the lower end of the stacker. Fig. 9 is a view in side elevation with some parts sectioned and others removed, showing the chain-tightener which 55 coöperates with the straw-carrier-driving chain. Fig. 10 is a horizontal section taken on the line $x^{10} x^{10}$ of Fig. 9. Fig. 11 is a detail view, in front elevation, showing a portion of the stacker-hood with one of my improved 60 curtain-holders applied thereto. Fig. 12 is a transverse section taken approximately on the line $x^{12} x^{12}$ of Fig. 1. Fig. 13 is a plan view illustrating the means by which the stacker-truck is connected to the stacker-frame and the rear axle thereof. Fig. 14 is a transverse section taken approximately on the line $x^{14} x^{14}$ of Fig. 5^a looking toward the 65 thresher; and Fig. 15 is a detail view, in longitudinal vertical section, illustrating the relation of the straw-delivery hood to the receiving end of the stacker.

Of the ordinary parts of the stacker it is sufficient for the purposes of this case to specifically note the stacker-case 1, the hood 2, 75 the rear wheels 3, the rear axle 4, and the straw-delivery shoe 5.

I support the lower end of the stacker on a truck which is pivotally connected or hinged with freedom for vertical movements to the 80 rear portion of the thresher-frame. In the illustration given the frame a of the stacker-truck is of skeleton form and is pivoted at its forward end by means of a shaft a' to hinge-straps a^2 , which in turn are detachably secured to the adjacent beams of the stacker-frame by means of nutted bolts a^3 .

At its free or outer end the frame a is supported by a wheel-beam a^4 , which is pivoted thereto at its intermediate portion by a pivot-bolt a^5 , which permits it to oscillate in a vertical plane transversely of the frame a . At its end the wheel-beam a^4 is provided with caster-wheels a^6 , the upper ends of the caster-brackets a^7 being secured by vertical 85 swivels a^8 to the ends of the said wheel-beam. Links a^9 connect the ends of the said wheel-beam with the sides of the frame a , and while they permit said beam the necessary vertical movements they hold the said wheel-beam against oscillation in a horizontal plane, 90 and thereby relieve the pivot-bolt a^5 from 95 100

strains which would otherwise be put upon the same in turning a curve with the machine.

On its upper face the truck-frame *a* is provided with an annular track or supporting-ring *a*¹⁰, and on this track the wheels *b* of an oscillating frame *b'* are mounted to work to support the said frame. Rigidly secured on and carried by the oscillating frame *b'* is a broad and longitudinally-extended rectangular frame *c*, which, with the arrangement illustrated, constitutes what may be well considered as the "receiving-section" of the stacker. This stacker-section *c* has a deck-section *c'* and is provided at its outer end with a transversely-extended hinge strip or leaf *c*² for a purpose which will be presently noted. Above the deck *c'* the sides of the frame *c* are provided with inturned flanges *c*³, and at its inner end the frame *c* is provided with a transversely-extended shaft *c*⁴, which is provided with a pair of laterally-spaced sprockets *c*⁵.

The vibrating straw-delivery shoe *s* is provided with an inclined and stepped or corrugated discharge-section *d*, which overlies the sprocket *c*⁵ and the inner end of the deck *c'*.

The stacker proper is made up of a body-section *f* and an extensible section *f'*. The body-section *f* is pivoted at its lower end to the outer portion of the frame-section *c* in the oscillating frame *b'*. This pivotal or hinge joint is in the illustration given in the drawings formed by pivotally-connected straps or hinge-irons *f*², that are rigidly secured to the said sections *f* and *c*. A transverse shaft *h* pivotally connects the irons *f*².

To the under edges of the sides of the stacker-section *f* long racks *f*³ are rigidly secured, as best shown in Fig. 6. The extensible stacker-section *f'* is mounted to work extensibly or telescopically immediately below the said racks *f*³, and to suitably mount the said stacker-section *f'* on said section *f* the racks *f*³ are provided with inwardly-projected ledges or flanges *f*⁴, and said stacker-section *f'* is provided with a plurality of keeper straps or brackets *f*⁵, the upper ends of which are hooked or bent, so as to engage over the adjacent flanges *f*⁴ of the said racks *f*³.

Suitably mounted in the lower or inner end of the extensible stacker-section *f'* is a transverse shaft *f*⁶, that is provided near each end with a pinion *f*⁷, which meshes with the corresponding adjacent rack *f*³. By positively rotating the shaft *f*⁶ and pinions *f*⁷ the extensible stacker-section may be given its desired movements. This positive movement of said shaft and pinions is effected by a novel device, to be hereinafter noted.

The stacker-sections *f* and *f'* are provided, respectively, with decks *f*⁸ and *f*⁹. Near its upper end and above the upper end of the deck *f*⁸ the stacker-section *f* is provided with a transverse shaft *f*¹⁰, which in turn is provided with a laterally-spaced pair of sprockets *f*¹¹.

The delivery end of the extensible stacker-section *f'* is turned downward, as shown at

*f*¹², to afford a better delivery of the straw to the stack, as set forth and claimed in my prior patent, above noted. Mounted in suitable bearings at the junction of the sections *f'* and *f*¹² is a transverse shaft *f*¹³, and at the outer end of said section *f*¹² is another transverse shaft *f*¹⁴, which shafts are provided, respectively, with pairs of sprockets *f*¹⁵ and *f*¹⁶. A short deck *f*¹⁷ on the section *f*¹² extends between the sprockets *f*¹⁵ and *f*¹⁶.

Depending from the stacker-section *f'*, below the shaft *f*¹³, one at each side of the machine, is a pair of guide-brackets *f*¹⁸, in which bearing-boxes *f*¹⁹ are free to move up and down. Said boxes *f*¹⁹ have depending stems *f*²⁰, on which springs *f*²¹ are placed to yieldingly hold said boxes upward. A transverse shaft *f*²², provided with a pair of sprockets *f*²³, is mounted in said pair of bearing-boxes *f*¹⁹.

At the outer end and at each side of the body-section *f* of the stacker is a pair of brackets *f*²⁴, which are provided at their lower ends with retaining-rollers *f*²⁵, that engage the under edge of the extensible stacker-section *f'* and form a support, over which the same may be freely extended or retracted.

The free or movable end of the stacker is supported by a device which in its broader features is the same as that claimed in my patent above mentioned; but the device herein illustrated embodies some minor novel features. Of the parts of the construction illustrated, *g* indicates a floating lever, provided at its ends with antifriction guide-pulleys *g'*, held by sockets *g*².

*g*³ are ropes or flexible connections that run one over each of the guide-pulleys *g'*, each having one end attached to the extensible stacker-section *f'* and another end attached to the body-section *f*, this latter connection, as shown, being made directly to a bracket *g*⁴ on the said section *f*. As shown, a pair of ropes *g*⁵ are connected to the central portion of the floating lever *g*, and at their other ends these ropes are wound on a windlass-shaft *g*⁶, mounted in suitable bearings on the top of the thresher-frame and provided with a sprocket *g*⁷. On their way from the lever *g* to the shaft *g*⁶ the supporting-ropes *g*⁵ pass over a guiding device formed by a horizontal roller *g*⁸ and three vertical rollers *g*⁹, which rollers are all suitably mounted in a supporting-frame *g*¹⁰, rigidly secured on the top and forward portion of the thresher-frame 1. The roller *g*⁸ resists the downward strain on the ropes *g*⁵, and the rollers *g*⁹ resist the lateral strains which are put upon the said ropes when the stacker is swung from side to side.

To enable the operator to readily control the winding and unwinding movements of the windlass-shaft *g*⁶, a sprocket-chain *g*¹¹ is run over the sprocket *g*⁷ on said windlass-shaft and over a lower sprocket *g*¹², which is suitably mounted in a bracket *g*¹³ on the side of the thresher-frame and is provided with the crank-handle *g*¹⁴, by means of which it may be turned, and with a ratchet-wheel *g*¹⁵, with

which a retaining-pawl g^{16} coöperates to hold the stacker in whatever elevated position it may be set by the movement of the said crank g^{14} .

5 An endless conveyer made up of slats k and sprocket-chains k' runs over the sprockets c^5 and f^{11} on the shafts c^4 and f^{10} , respectively, and over the decks c' and f^8 of the stacker-sections c and f , respectively. On its way 10 up and in passing the pivotal connection f^2 between the sections f and c the sprocket-chains k' run under inwardly-projected guide strips or flanges k^2 on the lower ends of the side strips of said section f , the lower 15 ends of these straps k^2 being turned upward to insure the proper entry of the slats k . In passing downward under the said hinge f^2 the chain passes under and is guided by antifriction guide-wheels or idlers k^3 . The 20 hinged leaf c^2 , heretofore noted as connected to the outer edge of the deck c' of the receiving-section of the stacker, overlaps the lower and inner end of the stacker f and keeps the 25 gap between the sections f and c always closed with a smooth joint, so that the straw, as well as the endless conveyer k k' , may freely pass. An endless conveyer made up of slats n and sprocket-chains n' runs over sprockets o on a transverse shaft o' , which shaft is mounted 30 in the lower end of the extensible stacker-section f' , and also over the sprockets f^{15} and f^{16} on the shafts f^{13} and f^{14} , respectively, and over the sprockets f^{23} on the shaft f^{22} of the belt-tightener.

35 The driving connections for the endless conveyers of the stacker will now be considered.

At one end the shaft a' , which is located at the pivotal connection between the stacker-truck and the thresher-frame, is provided 40 with a sprocket p and at its other end with a pulley p' , over which pulley a power-driven belt (not shown) would run. A sprocket-chain p^2 runs over the sprocket p and over another sprocket p^3 on one end of the transversely-extended shaft p^4 , mounted in bearings p^5 on the under side of the truck-frame a . A short vertical shaft p^6 , mounted in suitable 45 bearings p^7 on the frame a and at the axis of the annular track a^{10} , is provided at its lower end with a bevel-gear p^8 and at its upper end with a bevel-gear p^9 . A bevel-gear p^{10} on the shaft p^4 meshes with a pinion p^8 and the bevel-wheel p^{11} on a transverse shaft p^{12} meshes with a pinion or bevel-gear p^9 . The shaft p^{12} 50 is mounted in suitable bearings carried by the oscillating frame b' , and at one end—as shown, its left-hand end—it is provided with a sprocket p^{13} . A sprocket-chain p^{14} runs over the sprocket p^{13} and over a sprocket p^{15} 55 on the shaft c^4 , which drives the endless conveyer k k' . At its right-hand end the said shaft c^4 is provided with a sprocket p^{16} , over which and another sprocket p^{17} on the right-hand end of the shaft h a sprocket-chain p^{18} 60 runs. At its right-hand end the said shaft h is provided with another sprocket p^{19} , over which and the sprocket p^{20} , which is loosely

1 mounted on the right-hand side of the stacker-section f , near its outer end, a long sprocket-chain p^{21} is mounted to run. On its right-hand end the shaft o' , heretofore noted as being mounted in the lower end of the extensible stacker-section, is provided with a sprocket p^{22} , which is loosely mounted thereon, but is provided with pawls p^{23} , which coöperate with the ratchet-wheel p^{24} , and is keyed or otherwise rigidly secured on the said shaft o' . The pawls p^{23} and coöperating ratchet-wheel p^{24} cause the said sprocket p^{22} to positively drive the endless conveyer of the extensible stacker-section when said sprocket is driven in the direction indicated by the arrow marked on Fig. 9, but permit the said conveyer to move without action on the said conveyer when turned in a reverse direction. 85 The purpose of this construction will more clearly appear a little later on. The sprocket-chain p^{21} , which runs over the sprockets p^{19} and p^{20} , runs under and in engagement with said sprocket p^{22} , and the said chain is held for 90 a proper engagement with the said sprocket p^{22} by a pair of idlers p^{25} , as shown in the form of sprockets which are mounted in the opposite ends of a lever or support p^{26} , which is pivoted on the shaft o' .

95 As is obvious, when the pulley p' is driven in the proper direction motion will be transmitted through the intermediate connections described, and the endless conveyers k k' and n n' will be driven as indicated by the arrow marked on Figs. 5 and 5^a. The downwardly-moving under portion of the endless conveyer k k' will under the driving action be kept taut, while the upwardly-moving upper section of the same will be kept slack, thus 100 causing but very little friction due to the turning of the conveyer at the hinge or pivot between the sections f and c .

105 Were it not for the pawl-and-ratchet device p^{23} and p^{24} the downward or inward movement of the extensible stacker-section at a time when the stacker is idle and its driving mechanism stationary would run the endless conveyer of the said extensible stacker-section backward; but with the said pawl-and-ratchet device the pawl member slips over the ratchet member and prevents such backward-driving action.

110 As previously stated, to extend the extensible stacker-section requires a positive movement of the rack-engaging pinions f^7 , which are on the shaft f^6 . The device which I employ to accomplish this result is somewhat similar to the device just illustrated and 115 which is shown on the right-hand side of the machine for imparting motion to the conveyer of the extensible stacker-section. This device may be briefly described as follows: The body-section f of the stacker is provided 120 at its upper and lower ends, respectively, and on its left-hand side with a pair of sprockets r and r' , the former of which is an idler or 125 guide sprocket and the other of which is a driver and is suitably mounted in a bracket

r^2 on the said stacker-section f . The driving-sprocket r' has a hand-crank r^3 and a ratchet-wheel r^4 . A retaining-pawl r^5 , pivoted on the side of the stacker-section f , operates with said ratchet-wheel r^4 . A sprocket-chain r^6 runs over the sprocket-wheels r and r' and under and in engagement with the sprocket-wheel r^7 , which is rigid on the left-hand end of the shaft f^6 . The chain r^6 is guided and held for proper engagement with the sprocket r^7 by means of a pair of chain-tighteners or guides r^8 , which, as shown, are in the form of sprocket-wheels and are mounted one in each end of a lever or support r^9 , which is pivoted at its intermediate portion on the shaft f^6 . With this construction by turning the hand-crank r^3 the chain r^6 may be moved either in one direction or the other at will, and the sprocket r^7 , shaft f^6 , and pinions f^7 may be turned in either desired direction. As before stated, by turning the pinions f^7 in one direction or the other they may be caused to travel over the coöperating racks f^8 , and thereby extend or retract the extensible stacker-section f' . As the sprocket r^7 is rotated by the movement of the sprocket-chain r^6 it will travel either upward or downward over said chain, and this movement is permitted without varying the slack of the chain to any material extent by the action of the coöperating chain guides or sprockets r^8 , which travel with the said sprocket r^7 . As is evident, the retaining-pawl r^5 , previously noted, serves to lock the sprocket-chain r^6 , so that the extensible stacker-section f' will be held wherever set against the action of gravity.

The body-section of the stacker is provided with longitudinally-extended wind-shields s , that project upward from the sides thereof and are preferably detachably secured to a plurality of small keepers s' . The extensible stacker-section f' is provided with longitudinally-extended wind-shields that project upward from the sides thereof and overlap the sides of the stacker-section f . These wind-shields s^2 are arranged to clear all parts of the driving-gear and other parts of the stacker, so that they do not interfere with the adjustments of the extensible stacker-section.

The hood 2 of the thresher is formed or provided with a hinged and segmental delivery-section 2^a , which, as will be noted by reference to Fig. 2, is turned inward, so that it will deliver the chaff and straw blown against it backward toward the center of the receiving-section c of the stacker. The section 2^a being adjustable permits the same to be set in different positions, so as to vary its point of delivery onto the endless conveyor k k' .

It is desirable to discharge or deliver the straw and chaff onto the oscillating receiving-section c of the stacker at its central portion or on a transverse line approximately intercepting its pivot for the reason that the forward portion of said section c is vibrated

out of line with the most outwardly extended portion of the hood.

The openings at the sides of the hood 2 and above the receiving-section c of the stacker are normally closed by vertically-adjustable curtains t , which are tacked or otherwise secured to the said hood at their upper edges and are provided at their lower edges with cleats t' . The cleats t' are adjustably secured at their inner ends between the sides of the stacker-frame 1 and guide-rods t^2 , the ends of which are screw-threaded and passed through the sides of said stacker-frame and provided at their outer ends with thumb-nuts t^3 , as best shown in Fig. 12. At their outer ends said cleats t' are pivoted to the lower ends of vertical rods t^4 , which work vertically through projecting supports p^5 85 from the hood 2 and are adjustably secured thereto by set-screws t^6 .

The side curtains t may be easily raised at their inner ends, so as to give easy access to the screens and interior mechanism of the threshing-machine for the purpose of inspection or repair, simply by pushing the inner ends of the strips t upward, the depending end of the supporting-rod t^4 serving as a pivot for the coöperating cleat t' .

In traveling a curve with the threshing-machine having the stacker-truck and stacker attached thereto a great deal of strain would naturally be put upon the pivotal connection between the truck-frame and the thresher-frame. To relieve this pivotal connection as much as possible from such strains, I connect the rear portion or free end of the stacker-truck frame a to the rear axle 4 of the thresher by means of a pair of crossed tie-rods w , this construction being best illustrated in Fig. 13.

When the threshing-machine, with the attachment above described, is drawn over uneven ground, and all ground is of course more or less uneven, the pivotal connection between the thresher-frame and the stacker-truck frame a will permit the rear or outer end of the stacker to move up and down with respect to the wheels of the threshing-machine, and the pivotal connection between said truck-frame a and the wheel-beam a^4 will permit the caster-wheels a^6 to raise and lower one with respect to the other. These noted adjustments prevent the weight of the machine and attachment from being shifted from one wheel to the other in undue proportion in running over irregular ground, and thus prevent excessive strains on the framework of the machine and other parts. The caster-wheels permit the free lateral movements of the rear end of the truck-frame in traveling curves. All these actions contribute to give the most satisfactory results.

What I claim, and desire to secure by Letters Patent of the United States, is as follows:

1. The combination with a thresher, of a stacker and a stacker-truck, said truck comprising a frame pivoted or hinged to the

thresher-frame for vertical movements, a wheel-beam pivoted to the free or rear portion of said truck-frame, and a pair of supporting-wheels mounted on said wheel-beam, substantially as described.

2. The combination with a thresher, of a stacker and a stacker-truck, said truck comprising a frame pivoted or hinged to said thresher-frame for vertical movements, a wheel-beam pivoted at its intermediate portion to the free or rear portion of said truck-frame, and provided on opposite sides of its pivot with caster-wheels, substantially as described.

15 3. The combination with a stacker, of a stacker-truck upon which said stacker is mounted, said truck comprising a frame, a wheel beam or support pivoted to the rear portion of said frame and provided on the opposite sides of its pivot with supporting-wheels, and links or connections tying the free ends of said wheel-beam to said truck-frame, but permitting the free vertical oscillations of the same, substantially as described.

25 4. The combination with a stacker having an extensible section, of a rack on the body-section of said stacker, a pinion mounted on the extensible stacker-section and meshing with said rack, and a device for moving said pinion comprising a sprocket connected thereto, a sprocket-chain running over the said sprocket and over suitable guides, and a driving-sprocket on the body-section of said stacker engaging said sprocket-chain, substantially as described.

35 5. The combination with a stacker having an extensible stacker-section, of a rack on the body-section, a pinion carried by the extensible stacker-section and meshing with the said rack, and a device for rotating said pinion comprising a driven sprocket movable with said pinion, a pair of coöperating chain-guides one on each side of said sprocket, a sprocket-chain running over said driven sprocket and its coöperating chain-guides, and a driving-sprocket mounted on the body-section and engaging said sprocket-chain, the said parts operating substantially as described.

45 6. The combination with a stacker having an extensible section, of the racks f^3 on the body-section of said stacker, the transverse shaft f^6 carried by said extensible stacker-section and provided with the pair of pinions f^7 meshing one with each of the racks f^3 , the driven sprocket r^7 on said shaft f^6 , the lever or wheel-support r^9 mounted on said extensible stacker-section, and provided with the pair of guide wheels or sprockets r^8 , the sprocket-chain r^6 running over said driven sprocket r^7 and guide-sprockets r^8 and over suitable guides on the body-section of the stacker, said latter guides comprising the sprocket r' provided with a hand-crank r^3 , substantially as described.

55 7. A stacker constructed with an extensible section, provided with longitudinally and vertically extended wind-shields that are formed

independent of the sides of said extensible stacker-section and overlap the sides of the body-section of the stacker and telescope therewith without interference with the driving mechanism, or other parts, substantially as described.

8. The combination with a stacker having an extensible stacker-section, of endless conveyers running over said stacker-sections, and means for driving the conveyer of said extensible section comprising a driven sprocket-chain running over suitable guides on the body-section of the stacker, a sprocket on the extensible stacker-section driven by said sprocket-chain and in turn driving the endless conveyer thereof, and a one-way clutch in the connection between said driven sprocket and the conveyer driven thereby, substantially as described.

9. The combination with a stacker having an extensible section, of endless conveyers mounted on the said stacker-sections, and a drive for the conveyer of the extensible stacker-section, comprising sprockets or wheels on the lower stacker-section, a driven sprocket or wheel on the lower end of the extensible stacker-section, a flexible endless driving connection running over the said wheels, a bracket or lever pivoted for movement on the axis of said driven wheel, a pair of guide projections one at each end of said pivoted bracket or lever engaging the said driving connection on opposite sides of said driven wheel, and a one-way clutch in the connection between said driven wheel and the conveyer driven thereby, substantially as and for the purposes set forth.

10. The combination with a stacker having an extensible section, of a rack on the body-section of the stacker, a pinion mounted on the extensible section and meshing with said rack, and means for rotating said pinion comprising a driven sprocket-wheel rotating with said pinion, a driving-sprocket and a guide sprocket or wheel on the body-section of the stacker, a lever or bracket pivoted on the axis of said pinion and said driven sprocket, a pair of guide projections one on each end of said pivoted bracket or lever, and a sprocket-chain running over said driving-sprocket and guide sprocket or wheel on the said body-section and over the said driven sprocket and chain-guides of the extensible stacker-section, substantially as described.

11. The combination with a stacker having an extensible section, of the racks f^3 on the body-section of the stacker, provided with the extended flanges f^4 , the transverse shaft f^6 on the extensible section having the pinions f^7 meshing with said racks f^3 , and the straps or brackets f^5 secured to said extensible stacker-section and engaging the said rack-flanges f^4 to secure said extensible stacker-section for longitudinal movements on the said body-section, substantially as described.

12. The combination with a thresher pro-

- vided at the rear side portions of its case or framework with the clamping-rod t^2 with screw-threaded ends and nuts t^3 , of the side curtains t secured at its upper edge and provided at its lower free edge with the strip or cleat t' , and the adjusting-rod t^4 working through supports t^5 and subject to set-screws t^6 , said parts operating substantially as and for the purposes set forth.
13. The combination with a thresher, of side curtains pivotally supported at their outer ends from the rear side portions of the thresher-case and free for vertical movements at their inner ends, for affording ready access to the screens of the thresher, substantially as described.
14. The combination with a thresher, of a stacker-section or straw-delivery device receiving therefrom and mounted for lateral

oscillations, and a hood projecting rearward from said thresher-case and provided with a segmental straw-delivery section, which delivery-section is hinged or adjustably secured to the body-section of said hood, substantially as and for the purposes set forth. 25

15. The combination with a thresher, of adjustable side curtains applied to the rear end thereof, which side curtains are pivotally connected at their outer portions for vertical adjustments at their inner portions, substantially as and for the purposes set forth. 30

In testimony whereof I affix my signature in presence of two witnesses.

JAMES N. WILSON.
